(57) **CLAIM**

The ornamental design for a control switch for heated steering wheel as shown and described.

DESCRIPTION

FIG. 1 is a perspective view of a control switch for heated steering wheel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof; and,

FIG. 8 is a perspective view illustrating a control switch for heated steering wheel showing my design shown in a state of use.

The broken lines shown in the figures are included for illustrating unclaimed portions of the control switch for heated steering wheel and form no part of the claimed design.
